UNITED STATES PATENT OFFICE.

SOLOMON WILE, OF ROCHESTER, NEW YORK.

SLICING-MACHINE.

1,350,048.

Specification of Letters Patent. Patented Aug. 17, 1920.

Application filed November 10, 1919. Serial No. 336,962.

To all whom it may concern:

Be it known that I, SOLOMON WILE, a citizen of the United States, and resident of Rochester, in the county of Monroe and 5 State of New York, have invented certain new and useful Improvements in Slicing-Machines, of which the following is a specification.

The present invention relates to slicing 10 machines and more particularly to the type in which a rotary knife is employed in connection with a table moving transversely of the turning axis of the knife, an object of this invention being to provide an improved 15 means through which may be effected a relative movement between the table and the knife in the direction of the axis of turning. Another object of the invention is to provide 20 a novel feeding mechanism for feeding the knife in the direction of its axis. A further object of the invention is to provide an automatic means which will effect a relative movement between the knife and the work support in the direction of the axis of the 25 knife.

To these and other ends, the invention consists of certain parts and combinations of parts, all of which will be hereinafter described, the novel features being pointed out 30 in the appended claims.

In the drawings:

Figure 1 is a plan view of a slicing machine embodying the present invention;

Fig. 2 is a plan view of the slicing machine with the work support removed;

Fig. 3 is a view of the slicing machine in side elevation;

Fig. 4 is an enlarged section on the line 4—4, Fig. 1;

Fig. 5 is a sectional view on the line 5—5, Fig. 4;

Fig. 6 is a section on the line 5—5, Fig. 4, looking in the direction opposite to the view shown in Fig. 5;

Fig. 7 is a detail view of the breakable connection between the cutter shaft and the support for the material;

Fig. 8 is a section on the line 8—8, Fig. 1;

Fig. 9 is a section on the line 9—9, Fig. 4;

Fig. 10 is a detail view of the dog which effects the automatic movement of the knife in the direction of its axis of turning;

Fig. 11 is a view of the dog shown in Fig. 10 from the under side of said dog;

Fig. 12 is a detail view showing the man-

ner in which the dog co-operates with the breakable connection; and

Fig. 13 is a detail view of the means for holding the material upon the support.

Referring more particularly to the drawings, 1 indicates the frame of the machine which may be secured to any suitable supporting member such as a board 2. This frame embodies in this instance, two side members and carries a support 3 for the material to be sliced, and a rotary cutter 4 which preferably is in the form of a cutting disk with a peripheral cutting edge. The cutter and the work support are so formed that the work support may move transversely of the turning axis of the cutter while provision is made whereby a relative movement between the cutter and the support in the direction of the axis of the cutter may take place. In this embodiment, 70 this relative movement is effected by moving the cutter in the direction of its axis, but it will be apparent from some points of view, that the invention is not limited to producing this relative movement by a movement 80 of the cutter.

In order that the support for the material may partake of its movement transversely of the axis of the cutter, this support may have two guides 5 preferably on its under side and secured at opposite ends in blocks 6. These guides, in this instance, travel in bearings 7 formed at the upper ends of the frame pieces, the blocks 6 co-operating with the side pieces to limit the 90 movement of the support for the material in its two directions of movement.

The cutter 4 is preferably secured to a shaft 8 which connects to two frame pieces 1 and has a rotary as well as an axial movement in said frame pieces. This shaft may be provided with a screw 9 and on this screw a nut or internally threaded sleeve 10 may operate. This sleeve is held against axial movement in any suitable manner as 100 in the manner hereinafter described.

It is apparent that if the shaft is permitted to turn freely in the nut, the shaft will move axially whereas, if the nut is locked to the shaft, the nut will turn and at 105 the same time the shaft will be held against axial movement. In order to effect this connection and disconnection of the nut with the shaft, a breakable connection is provided which in this instance consists of a 110

sliding key 11 movable in a longitudinal extending groove or way 12 in the shaft and adapted at one end to enter into a notch or opening 13 in the nut. For the purpose of 5 operating this key, the latter has a collar 14 rigidly secured thereto and surrounding the shaft 8. This collar is acted upon by a helical spring 15 which surrounds the shaft and abuts the sliding collar 14 at one end 10 and at its other end a collar 16 is rigidly and adjustably secured to the shaft 8 by a set screw 17. The spring normally holds the key 11 in connection with the nut 10. In order to effect the disconnection of the 15 nut with the shaft so as to permit the shaft to turn in the nut, the collar 14 may be provided with an annular groove 20. In this groove a yoke 21 operates, said yoke being secured to the upper end of an arm 22 20 which at its lower end is pivoted at 23 to the supporting base 2. An arm 24 extends laterally from the lower end of the arm 22 and upon the depression of the arm 24 the collar 14 will be moved to move the key 11 25 out of connection with the nut. Automatic means may also be provided for breaking the connection between the nut and the screw shaft, one embodiment of such means being hereinafter fully described.

20 Any suitable means may be employed for moving the support 3 for the material to be sliced transversely of the axis of turning of the cutter shaft. In this embodiment, this support movement is produced through a 35 connection with the cutter shaft and to this end the nut 10 is provided on its periphery with teeth 25 which coöperate with upwardly presented teeth on a rack 26, this rack being suspended by brackets 27 from 40 the under side of the support 3. It is apparent that rotation of the shaft 8 by any suitable means such as a crank handle 28, when the nut 10 is interlocked with the shaft, will produce a movement of the support 45 transversely of the shaft through the rack 26 and the gear teeth 25. The rack bar 26 is utilized for preventing the axial movement of the nut 10 and to this end, the nut is provided with annular flanges 10^a on opposite sides of the teeth 25, these flanges co-operating with opposite sides of the rack bar to prevent the axial movement. Beneath the rack bar at a point directly below the nut, one of the frame members may be 50 provided with a projecting portion 29 which coöperates with the under side of the rack bar to maintain coöperation between the rack bar and the teeth 25.

With the end in view of effecting the 60 automatic shifting of the cutter shaft in the direction of the axis of said shaft, the support 3 may be provided on its under side with a latch or detent 30 pivoted at 31 and having a tapered free end 32. The thickness of this free end is less than the dis-

tance between the collar 14 and the nut 10 when the collar is in the position to hold the nut so that the shaft is interlocked therewith, whereas, the thickness of the latch or detent in rear of said tapered portion is 70 greater than the distance between the collar 14 and the nut 10. The pivoted latch or detent 30 is so arranged on the support that when the latter has reached one end of its movement, the tapered end will pass between the collar 14 and the nut 10 and move said collar in the direction of the axis of the shaft 8 so as to break the connection between the shaft and the nut, permitting the shaft 8 to turn in the nut and in this way 80 move the cutter axially toward the support 3 for the material. In this embodiment, the shaft 8 makes only one rotation before the interlocking connection between said shaft 8 and the nut 10 is reestablished. This reestablishment is effected in this instance by a projection 33 on the face of the collar 14 opposed to the nut. The projection engages the under side of the latch 30 and moves said latch upwardly in the manner shown 85 in Fig. 12, out of the position between the collar 14 and the nut 10, after which the spring 15 will move the collar 14 so that the key 11 will reestablish connection between the nut 10 and the shaft 8. The dog 90 or latch being wider than the distance between the collar 14 and the nut 10, will rest upon these parts so that, when the shaft is rotated in a reverse direction, the dog will be carried away from such parts to the 100 other extreme movement of the support 3 to again separate the parts upon the next approach thereto. In order to limit the axial movement of the shaft in two directions, two stops 34 and 35 are provided, one of 105 these stops coöperating with the collar 16 and the other stop coöperating with a collar 36 on the shaft, both stops being in the form of screws and being adjustable.

The material may be held on the support 3 110 in any suitable manner. It is preferred however, to provide the upper surface of the support with a plurality of projections 37 and to mount on the support, a plunger 38 having a clamping head 39 at its lower 115 end and a handle 40 at its upper end by which the clamping head may be elevated against the action of the spring 41 which surrounds the plunger 38. The plunger 38 may be guided in a bracket 42 which is supported from the support 3. The operation of the invention will be understood from the foregoing, but it may be summarized as 120 follows:

The meat or other material is secured 125 upon the support 3 under the clamping head 39 to project beyond the support 3 in the path of the cutter 4. The crank handle is then turned which moves the support 3 transversely of the cutter shaft 8 and causes 130

the rotary blade 4 to slice the material on the support. Upon the return movement of the support 3, the latch or dog 30 will pass between the collar 14 and the nut 10, thus 5 breaking the connection between the shaft 8 and the nut, and permitting the shaft to make one rotation in the nut, after which the connection between the nut and the shaft is reestablished. This movement of the 10 shaft in the nut shifts the shaft axially so that upon the movement of the support 3 in the opposite direction another slice will be cut from the material. This operation is continued until the knife or cutter 4 approaches the proximate edge of the support 3. When this position is reached, the lever arm 24 is depressed, shifting the collar 14 to break the connection between the shaft and the nut 10. The shaft is then turned in 15 a direction to cause the cutter or knife to be moved away from the support 3 and, when the desired position of the knife is reached, the lever 24 is released permitting the connection between the shaft 8 and the 20 nut to be reestablished.

From the foregoing it will be seen that there has been provided a rotary cutter movable axially and combined with a support for the material to be sliced movable 30 transversely of the axis of rotation of the cutter. A driving connection is provided between the shaft of the cutter and the support, this driving connection preferably being breakable so that the shaft may be moved axially independently of the support. Means is also provided whereby the cutter shaft may be moved automatically when the support reaches a certain position. This 35 automatic means is preferably in the form 40 of a dog carried by the support and coöperating with the breakable connection.

What I claim as my invention and desire to secure by Letters Patent is:

1. A slicing machine comprising a rotary 45 cutter movable in the direction of its axis, and a support for the material to be sliced movable transversely of the axis of rotation of the cutter.

2. A slicing machine comprising a rotary 50 and axially movable shaft, a cutter on said shaft, and a support for the material to be sliced movable transversely of the shaft and having connection with the shaft to be moved by the latter.

55 3. A slicing machine comprising a rotary and axially movable shaft having a screw thereon, a rotary cutter mounted on the shaft, a support for the material to be sliced movable transversely of the shaft, a nut 60 coöperating with the screw and held against axial movement, and means for holding the screw against turning in the nut.

65 4. A slicing machine comprising a rotary and axially movable shaft, a cutter on the shaft, a screw on the shaft, a nut through

which the screw operates, held against axial movement with the shaft, means for holding the screw against turning in the nut, a support for the material to be sliced movable transversely of the shaft, and a driving connection between the nut and the support for permitting the latter to be driven from the shaft. 70

5. A slicing machine comprising a rotary and axially movable shaft, a screw on said 75 shaft, a nut through which the screw operates, held against axial movement, means for holding the screw against turning in the nut, teeth on said nut, and a support for the material to be sliced movable transversely of 80 the shaft, and having connection with the nut to be driven thereby.

6. A slicing machine comprising a rotary and axially movable shaft, a cutter on the shaft, a screw on the shaft, a nut through 85 which the screw operates held against axial movement with the shaft, means for holding the screw against turning in the nut, teeth on said nut, a support for the material to be sliced movable transversely of the 90 shaft, and a rack connected to said support and meshing with the teeth on the nut.

7. A slicing machine comprising a rotary and axially movable shaft, a cutter mounted on said shaft, a screw on said shaft, a nut 95 in which the screw operates, means for holding the screw against turning in the nut, teeth on the nut, flanges on the nut on opposite sides of the teeth, a rack coöperating with the teeth to be moved by the nut, and 100 with flanges to hold the nut against axial movement, and a support for the material to be sliced having the rack connected thereto and being movable transversely of the shaft. 105

8. A slicing machine comprising a rotary cutter movable in the direction of its axis, a support for the material to be sliced movable transversely of the axis of rotation of the cutter, and means controlled by the support for effecting the movement of the cutter in the direction of its axis. 110

9. A slicing machine comprising a rotary shaft having a movement in the direction of its axis, a rotary cutter mounted on the 115 shaft, a support for the material to be sliced, movable transversely of the shaft, and driving connection between the shaft and the support having a breakable connection which will permit the shaft to move axially. 120

10. A slicing machine comprising a rotary and axially movable shaft, a cutter on said shaft, a support for the material to be sliced movable transversely of the shaft, and a driving connection between said shaft and the support having a breakable connection 125 which operates automatically to permit the shaft to turn without moving the support when the support reaches a certain position.

11. The combination with a rotary cutter 130

and a support for the material to be sliced, of means for effecting a movement of the support transversely of the axis of the cutter, and means for effecting a relative movement between the support and the cutter in the direction of the axis of the cutter, said means being controlled automatically when the support reaches a certain position.

12. A slicing machine comprising a rotary and axially movable shaft, a cutter on the shaft, a support for the material to be sliced movable transversely of the shaft, a screw on the shaft, a nut through which the screw operates, held against axial movement, means for holding the screw against turning in the nut, and a dog movable with the support and coöperating with said holding means to break connection between the nut and the screw when the support reaches a certain position.

13. A slicing machine comprising a rotary and axially movable shaft, a cutter mounted on the shaft, a screw on the shaft, a nut in which the screw operates held against axial movement, a support for the material to be sliced having a connection with the nut through which the support is moved, a spring pressed device for establishing connection between the screw and the nut so that the nut turns with the screw, a dog moving with the support to move said spring pressed device to break the connection between the nut and the screw, and a device

operated by the shaft for kicking the dog out of the path of the spring pressed device after the screw has been turned the desired distance in the nut.

14. A slicing machine comprising a rotary and axially movable shaft, a cutter on the shaft, a screw on the shaft, a nut through which the screw operates held against axial movement with the shaft, a support for the material to be sliced, a driving connection between the nut and the support, a key operating a way in the shaft to lock the nut to the shaft, a collar secured to said key, a spring acting on the collar to hold the key in interlocking connection with the nut, a dog moving with the support and adapted to pass between the collar and the nut to move the key out of connection with the nut, and a device on the collar adapted to displace the dog from its position between the collar and the nut after the screw has been turned in the nut to the desired position.

15. In a slicing machine, the combination with a rotary cutter and a support for the material to be sliced, of a mechanism for effecting a relative movement between said parts in the direction of the axis of the cutter comprising a rotary and axially movable shaft, a screw on the shaft, a nut operating on the screw and held against axial movement, and a releasable means for holding the screw against turning in the nut.

SOL. WILE.
